UNITED STATES PATENT OFFICE.

JAMES H. REINHARDT, OF EAST ORANGE, NEW JERSEY.

PRINTING-MACHINE.

1,100,256.

Specification of Letters Patent. Patented June 16, 1914.

Application filed March 4, 1912. Serial No. 681,375.

To all whom it may concern:

Be it known that I, JAMES H. REINHARDT, a citizen of the United States, and resident of East Orange, in the county of Essex and State of New Jersey, have invented certain new and useful Improvements in Printing-Machines, of which the following is a specification.

My invention has reference to printing upon continuous sheets, strips or webs of paper or the like, and is particularly adapted to simultaneously printing upon one or both sides of one or more sheets, strips, or webs as the same are fed.

My invention is adapted for simultaneously printing and gathering or assembling a plurality of sheets, strips or webs and for uniting them together for the production of pamphlets, signatures for books, and the like, whereby the gathered or assembled sheets or webs may be cut off to the desired lengths after being secured together.

My invention comprises novel details of improvement and combinations of parts that will be more fully hereinafter set forth and then pointed out in the claims.

Reference is to be had to the accompanying drawings forming part hereof, wherein,

Figure 1 is a partly broken side elevation of a printing machine embodying my invention; Fig. 2 is a plan view thereof, the sewing machine 30 being omitted; Fig. 3 is an enlarged detail side view of a portion of Fig. 1; Fig. 4 is an enlarged detail cross section on the line 4, 4, in Fig. 1, and Fig. 5 is an enlarged sectional view of the feeding and gumming devices.

Similar numerals of reference indicate corresponding parts in the several views.

In the drawings, the numeral 1 indicates a support of any suitable construction for the printing devices, which is shown carried by the extension 2 of frame 2. Support 1 is shown in the form of two spaced members (Fig. 1) carrying printing devices. I have shown a plurality of supports each for different sets of printing units or devices, and as the latter may all be substantially alike the description of one will suffice for all, as follows: 3, 3^a indicate type carrying or printing rollers of any well-known form, and 4, 4^a indicate the corresponding impression cylinders or rollers geared to the printing rollers respectively, between which pass sheets, strips or webs to be printed. In the example illustrated, the

cylinders 4, 4^a are respectively rotatively carried by arms or frames 6, 6^a that are journaled upon the shafts 7, 7^a of printing rollers 3, 3^a, which shafts are shown journaled upon the corresponding supports 1. The arms or frames 6, 6^a are connected by links 8 pivotally hung upon the shafts 9, 9^a of the printing cylinders 4, 4^a, whereby the latter are united for lateral similar movement. The arms 6 are arranged to be rocked whereby the corresponding arms 6^a are rocked, for which purpose the arms 6 are shown provided with extensions 6^b adapted to coact with the cam-ring 10 for rocking said arms. A spring 11, shown connected with link 8 and with frame 2^a, serves to cause arm 6^b normally to be pressed toward cam 10. A roller 12 is shown journaled at the end of arm 6^b to coact with cam 10.

While any suitable means may be provided for rotating the printing rollers 3, 3^a, I have shown a gear wheel 13 journaled in suitable bearings in frame 2 and adapted to be rotated by pulley 14, which gear wheel 13 meshes with gear 15 secured upon the shaft 7, whereby printing roller 3 will be rotated as gear wheel 13 revolves. To communicate corresponding motion to printing roller 3^a the shaft 7 is shown provided with a beveled gear 16 meshing with a beveled gear or pinion 17 secured at one end to shaft 18 journaled in suitable bearings upon support 1, and having at its outer end a beveled gear or pinion 19 meshing with a gear 20 on shaft 7^a. The arrangement shown is such that the printing rollers 3, 3^a are rotated in opposite directions because said printing rollers are on opposite sides of sheet or web 5 to print on opposite sides of the latter as it is fed to the left in Fig. 1. The gear 15 meshes with a gear 15^a for rotating cylinder or roller 4, and the rollers 3, 3^a are likewise geared together by gears. Any suitable inking devices, indicated generally at 21, 21^a are provided to apply ink to the type on the corresponding printing rollers 3, 3^a. The cam 10 is carried by gear 13 in such position as to rock the arms 6, and thereby through the links 8 to communicate a corresponding rocking motion to the arms 6^a, whereby the cylinders 4, 4^a are caused to have movement around the axes of printing rollers 3, 3^a.

Since I have illustrated a number of printing units or devices of the character set forth, arranged around gear 13 so that the gears 15 of each set of printing units

or devices are driven uniformly and simultaneously by gear 13, the various sheets or webs 5 may be separately or independently fed or may be fed to a common center or gathering point as illustrated in Fig. 1. To this end I have shown rollers 25, 26, suitably journaled upon frame 2, between which rollers the sheets or webs 5 pass, and which are thus gathered together. Said gathered webs may be fed by means of feeding rollers 27, 27^a, suitably journaled upon support 2^b (Fig. 5) and driven by a gear 28 on shaft 27^b of roller 27, and meshing with gear 13. Between the gathering rollers 25, 26 and the feeding rollers 27, 27^a means are provided for securing the gathered printed sheets or webs together. The means I have shown comprise a suitable sewing machine 30, which may be supported and operated in any wellknown manner, in position to stitch together the gathered or assembled sheets or webs 5, as by the line of stitching 31 (Fig. 2). By having the sheets or webs 5 secured together after printing they will be drawn or fed uniformly by the feed rolls 27, 27^a, so that proper registration of printed matter upon said sheets or webs will be effected, since the superposed or collected webs cannot creep with respect to each other.

Where a single-thread sewing machine is used I provide means for gumming the stitches 31 to prevent them from pulling out. For this purpose I have shown rollers 32, 33, between which the stitched sheets or webs pass, (Fig. 5), a gear 34 on the shaft of roller 32 meshing with an idle gear 35 that meshes with gear 28, whereby the rollers 32, 33 are rotated. Roller 32 is provided with a peripheral groove receiving an absorptive ring or brush 36, such as cord or rope, alined with stitching 31 of the sheets or webs 5, which ring or brush engages a gumming roller 37 dipping into a bath 38 of suitable gum, glue or the like, a transfer roller 39 in said bath being shown in engagement with roller 37, Fig. 5. Gear 35 may be secured to the shaft of roller 37 for rotating the latter.

The operation may be described as follows: With the machine adjusted as shown in Fig. 1 the several sheets, strips or webs 5 are passed between the corresponding sets of printing units or devices, from the guiding rollers α , whereby printing upon opposite sides of each sheet may be effected by type upon the corresponding printing rollers 3, 3^a, and such sheets are passed between the gathering or assembling rollers 25, 26, under the presser foot and needle of the sewing machine, and between the roller 27^a, 27^a, 32 and 33. The machine is then started and as gear 13 rotates in the direction of the arrow in Fig. 1, the feeding rollers 27, 27^a will cause the strips or webs 5 to be fed,

and the sewing machine will stitch the gathered or assembled sheets together, and thereby the latter will all be fed or pulled along uniformly because as they are secured together there can be no creeping of the sheets or webs, and during such time the printing rollers and cylinders will be rotated through the gearing, printing simultaneously upon the opposite sides of the sheets or webs. Of course, but one side of a sheet or web need be printed upon if desired. By means of cam 10 operating upon the arms 6^b, the latter will be rocked, and by the arrangement of the cams shown the arms 6^b will be moved outwardly gradually, but will more quickly be returned. The effect of this action is when arms 6^b are moved outwardly, that the cylinders 4, 4^a will be caused to move bodily, (while rotating) in a direction around the corresponding printing rollers, thereby advancing the printing contact toward the side from which the type is advancing to cause printing upon sheets or webs 5 more rapidly than if the impression cylinders remained in set position, the sheets or webs at all times moving at uniform speed, the termination of the type upon the printing rollers being in such position that as soon as the last of the printing by a printing roller has occurred, the corresponding arm 6^b will quickly return down cam 10 thereby drawing or returning the corresponding cylinders again toward the left in Fig. 1. By this means the time consumed in printing from a given length of type is reduced at each stroke. The extent of the type upon a printing roller may vary in the direction of the circumference of the roller, as desired, since as soon as the printing from one rotation of a printing roller has ceased the corresponding cylinder returns to the left in Fig. 1 quicker than the surface speed of the printing roller, and for the next impression the cylinder advances toward the type on the printing roller, while the sheet or strip 5 is being fed. Regulation of the time or distance of movement of the cylinders with respect to the printing rollers around the axes of the latter, may be made in accordance with the character of cam 10, which latter may be replaced, as desired, upon gear 13 according to the extent of the type placed upon the printing rollers.

While I have illustrated two printing rollers in a set or unit and two corresponding cylinders connected together for movement around such printing rollers, whereby printing may occur simultaneously on opposite sides of the sheet or strip, it will be understood that my invention may be carried out to a desired extent by the use of a single printing roller and its corresponding cylinder, also that in the latter case the movement of the cylinder around the printing roller may be accomplished as set forth. It will,

also, be understood, however, that so far as the arrangement set forth for gathering or assembling a plurality of sheets or webs, printing upon them, and securing them together, while the webs are being fed, may be accomplished, without utilizing the specific arrangements of printing rollers and their cylinders set forth, as, for instance, the cylinders may be caused to remain set with respect to the printing rollers by removing the cam 10 and holding the cylinder supports 6, 6^a rigid.

Changes may be made in the details of construction and arrangements set forth, within the scope of the appended claims, without departing from the spirit of the invention.

Having now described my invention what I claim is:—

20 1. A printing machine comprising a plurality of printing units, means for continuously and uninterruptedly feeding webs printed by said units, means for gathering the printed webs between the printing units 25 and the web feeding devices, a sewing machine for continuously stitching the gathered webs together, and means for applying adhesive material to the thread on one side of the webs, said sewing machine being located between the gathering means and the 30 web feeding and adhesive applying means.

2. A printing machine comprising a plurality of printing units, means for feeding webs simultaneously through the printing units, means for gathering said webs as fed, a sewing machine for continuously stitching said gathered webs together, said sewing machine being located between the printing units and the web feeding means, and gumming devices to apply gum to said stitching.

3. A printing machine comprising a plurality of printing units, means for feeding webs simultaneously through the printing units, means for gathering said webs as fed, a sewing machine for continuously stitching said gathered webs together, said sewing machine being located between the printing units and the web feeding means, and gumming devices to apply gum to said stitching, 50 said gumming devices being located on the web delivery side of feeding means.

4. A printing machine comprising a plurality of printing units, means for feeding webs simultaneously through the printing units, means for gathering said webs as fed, a sewing machine for stitching said gathered webs together, said sewing machine being located between the printing units and the web feeding means, gumming devices to apply gum to said stitching, said gumming devices comprising opposed rollers, one of said rollers having a peripheral absorptive brush alined with the stitching in the webs, and means for applying gum thereto.

65 5. A printing machine comprising a plu-

rality of spaced printing rollers, a cylinder opposed to each roller, the cylinder of one roller being on the side of the latter opposite to the cylinder of the other roller, means for simultaneously rotating said rollers, and 70 means for supporting said cylinders to have movement around the axes of their respective rollers.

6. A printing machine comprising a plurality of spaced printing rollers, a cylinder 75 opposed to each roller, the cylinder of one roller being on the side of the latter opposite to the cylinder of the other roller, means for simultaneously rotating said rollers, and means for supporting said cylinders to have 80 movement around the axes of their respective rollers, said cylinders being connected together to move simultaneously and co-extensively.

7. A printing machine comprising a plurality of spaced printing rollers, a cylinder 85 opposed to each roller, the cylinder of one roller being on the side of the latter opposite to the cylinder of the other roller, means for simultaneously rotating said rollers, and 90 means for supporting said cylinders to have movement around the axes of their respective rollers, said cylinders being connected together to move simultaneously and co-extensively, and means for moving said cylinders back and forth together.

8. A printing machine comprising a plurality of spaced printing rollers, a cylinder 100 opposed to each roller, the cylinder of one roller being on the side of the latter opposite to the cylinder of the other roller, means for simultaneously rotating said rollers, means for supporting said cylinder to have movement around the axes of their respective rollers, said cylinders being connected together 105 to move simultaneously and co-extensively, and a member having a plurality of cam-like portions to move said cylinders back and forth around the axes of their respective rollers.

9. A printing machine comprising a printing roller, means to rotate said roller, an impression cylinder adjacent the roller, means movably supporting the impression cylinder to move around the axis of said 115 roller while in impression relation to one another, and means operated with the roller rotating means to move said impression cylinder back and forth around the axis of said roller.

10. A printing machine comprising a printing roller, an impression cylinder adjacent the roller, means movably supporting the impression cylinder to move around the axis of said roller while in impression relation to one another, and a cam member adapted to move said impression cylinder 125 around the axis of its roller.

11. A printing machine comprising a printing roller, means to rotate the roller, 130

- arms journaled concentric with the axis of said roller, an impression cylinder journaled upon said arms, and means to move said arms and impression cylinder back and forth while said printing roller rotates, and while said roller and cylinder are in impression relation to one another.
12. A printing machine comprising a printing roller, arms journaled concentric with the axis of said roller, an impression cylinder journaled upon said arms, and a cam member adapted to move said arms while said roller and cylinder are in impression relation to one another.
13. A printing machine comprising a printing roller, arms journaled concentric with the axis of said roller, an impression cylinder journaled upon said arms, and a cam member adapted to move said arms while said roller and cylinder are in impression relation to one another, one of said arms having a projection to coact with said cam member.
14. A printing machine comprising a printing roller, a gear connected therewith, a gear meshing with the first named gear, a cam member operative with the second named gear, arms journaled concentric with the axis of said printing roller, a cylinder journaled on said arms adjacent said roller, and means for operating said arms by said cam member.
15. A printing machine comprising a printing roller, a gear connected therewith, a gear meshing with the first named gear, a cam member operative with the second named gear, arms journaled concentric with the axis of said printing roller, and a cylinder journaled on said arms adjacent said roller, one of said arms having a projection to coact with said cam member to move said arms around the axis of the roller.
16. A printing machine comprising a printing roller, a gear connected therewith, a gear meshing with the first named gear, a cam member operative with the second named gear, arms journaled concentric with the axis of said printing roller, a cylinder journaled on said arms adjacent said roller, means for operating said arms by said cam member, a second printing roller spaced from the first named roller, arms journaled concentric to the axis of said second roller, a cylinder journaled in said arms adjacent said second roller, and a connecting piece between the first and second named arms for operating them simultaneously and co-extensively.
17. A printing machine comprising a printing roller, a gear connected therewith, a gear meshing with the first named gear, a cam member operative with the second named gear, arms journaled concentric with the axis of said printing roller, a cylinder journaled on said arms adjacent said roller, means for operating said arms by said cam member, a second printing roller spaced from the first named roller, arms journaled concentric to the axis of said second roller, a cylinder journaled in said arms adjacent said second roller, and a connecting piece between the first and second named arms for operating them simultaneously and co-extensively, the second named cylinder being on the side of its roller opposite to the first named cylinder with respect to its roller.

Signed at New York city, in the county of New York and State of New York, this 1st day of March A. D. 1912.

JAMES H. REINHARDT.
